UNITED STATES PATENT OFFICE.

GEORGE F. SCOTSON-CLARK, OF NEW YORK, N. Y.

LACE.

1,282,129.

Specification of Letters Patent. Patented Oct. 22, 1918.

Application filed October 1, 1917. Serial No. 194,273.

To all whom it may concern:

Be it known that I, GEORGE F. SCOTSON-CLARK, a subject of the King of Great Britain, and a resident of the city of New York, 5 borough of Manhattan, in the county and State of New York, have invented a new and Improved Lace, of which the following is a full, clear, and exact description.

Among the principal objects which the 10 present invention has in view are: To provide a permanent rigid extremity integrally connected with the body of the lace; to provide a flat terminal for shoe and corset laces which will not separate from the body there- 15 of; to form a rigid terminal for laces without altering the external appearance of the same; and to simplify and cheapen the construction.

Drawings.

20 Figure 1 is a side view partially in section and on an enlarged scale of an end fragment of a lace;

Fig. 2 is a similar view, the core of the 25 lace being shown in section to disclose the strengthening member used in laces constructed and arranged in accordance with the present invention;

Fig. 3 is a similar view showing the end 30 of the lace as partially covered with cement;

Fig. 4 is a similar view showing the extreme ends of the lace drawn together over the opening in the core at the extremity of the stiffening member, the tips being coated 35 with enamel, shellac or other suitable covering.

Description.

As seen in the drawings, the lace has a 40 covering fabric 9. The fabric 9 is constructed in any approved manner. Laces having the fabric 9 and core 10 are conventional in the art. When constructed in accordance with the present invention, a small section 45 11 of wire, wood, bone or other stiff material is forced through the core 10, the outer end of the core 10, and fabric 9, protruding over the extreme end of section 11. When thus disposed, the end of the lace is dipped and permeated with a setting or hardening cement 50 or liquid and allowed to harden or set.

Just prior to the final hardening or setting of the cement and the material impregnated thereby, the fabric and core are cut or sliced by some tool adapted to draw the material toward the center of the lace. As shown best 55 in Fig. 4 of the drawings, the material is drawn over the opening in the core 10 to imprison or hold the section 11.

When the permeated material has become set and hard, the tip of the lace is further 60 treated by dipping in a varnish or other material to render the surface impervious to moisture.

It will be understood that the coating varnish may be colored or suitably treated to enhance the appearance of the lace, or may be made transparent to show the structure of the fabric 9.

The tip can be pressed in a finishing device 70 to give it a pointed end, if so desired.

It is obvious that when laces are provided with stiffened terminals or tips constructed as described, the same will not become separated from the body of the lace nor detract from the appearance of the lacing. It is also 75 obvious that the construction and arrangement are such that the cost thereof is materially reduced.

Claims.

80

1. A lace comprising a reinforced terminal section embodying a flexible core, a fabric covering therefor, a stiffening member centrally disposed in said core, and means for holding said member in said core, said means embodying a hardening cement incorporated in the structure of said core.

2. A lace comprising a reinforced terminal section embodying a flexible core, a fabric covering therefor, a stiffening member centrally disposed in said core, means for holding said member in said core, said means embodying a hardening cement incorporated in the structure of said core; and means closing said core over the end of said stiffening member, said means employing said cement, the same being drawn over the opening in said core prior to the final setting of said cement.

GEORGE F. SCOTSON-CLARK.
